UNITED STATES PATENT OFFICE.

JAMES ALEXANDER GLASS, OF DURHAM, ONTARIO, CANADA.

VENTILATING DEVICE.

981,635.

Specification of Letters Patent. Patented Jan. 17, 1911.

Application filed June 9, 1909. Serial No. 501,157.

To all whom it may concern:

Be it known that I, JAMES ALEXANDER GLASS, of the town of Durham, in the county of Grey, in the Province of Ontario, Canada, have invented certain new and useful 5 Improvements in Ventilating Devices, of which the following is the specification.

My invention relates to improvements in 10 ventilating devices for interiors of buildings, cars and the like, and the object of the invention is to devise a simple and effective 15 and inexpensive device, whereby not only will fresh air be supplied to a room or interior, but at the same time means provided whereby all foul air will be eliminated.

My invention consists of a casing or the 20 like designed to be placed underneath the window or opposite the opening in the wall and made in two parts, the upper part of 25 which has an orifice in the outside wall thereof and a series of horizontally disposed deflecting plates projecting inwardly from the front wall past each other, so as to form a circuitous passage-way terminating 30 at the top of the casing for the admission of the pure air and the lower portion being formed with end openings, and a central 35 opening, a substantially vertically disposed deflecting plate lying parallel to the central opening and vertically disposed inclined plates extending from the back and converging centrally toward the aforesaid plate and leaving an opening opposite such plate, and vertical passage-ways communicating 40 with the space to the inside of the inclined deflecting plates, the parts being otherwise constructed and arranged in detail as hereinafter more particularly explained.

Figure 1, is a vertical section showing a 45 window frame and casing with my ventilating device applied thereto. Fig. 2, is an outside view of the lower portion of the window showing the location of the device. Fig. 3, is a vertical section through the line 50 $x-x'$ Fig. 1. Fig. 4, is a horizontal section through the line $y-y'$ Fig. 1. Fig. 5, is a perspective detail of the ventilating device complete. Fig. 6, is a sectional view showing a modified construction of my device 55 made integral with the window sash. Fig. 7, is a sectional view showing a further modification showing it also integral with the window sash.

In the drawings like letters of reference 60 indicate corresponding parts in each figure. A is the window frame, B the upper sash

and C the lower sash. In this description I shall describe my invention as applied to the window, but it will, of course, be understood that I may with equal facility apply 60 it to any opening in the wall or place it in the wall itself, or form it in the slot itself. In the present illustration, however, I have shown my device underneath the bottom of the lower sash, such sash being raised, and 65 the front portion of the casing of the device extending underneath the same leaving an orifice beneath the bottom of the sash, and the top of the lowermost portion of the casing.

The casing comprises side walls D of step-like form having the upper projection D' 70 surmounted by a capping board or plate D². The intermediate portion D³ surmounted by a capping board D⁴, leaving a space near the 75 wall D⁵ and the lower front projecting portion D⁶ having a capping board D⁷ extending between the same and beneath the level of the upper front wall D⁸ leaving an orifice thereunder. D⁹ is the front board of 80 the lower portion or part of the casing, such front board D⁹ being secured to the end of the board D⁷.

2 and 3 are boards or plates extending 85 rearwardly from the front D⁸. The three 90 boards or plates D⁴ 2 and 3 are preferably equi-distant apart and have interposed between them the deflecting plates 4 and 5, which are equi-distantly disposed and form a circuitous passage-way 6 terminating at 95 the bottom in the opening 7 beneath the sash and the top 8. The pure fresh air passes through the opening 7 and through the circuitous passage-way 6 and out through the opening 8 into the interior of the room 100 or compartment, and the deflecting plates or boards D⁴ 2 and 3 and 4 and 5 serve to prevent, I find in practice, any draft from passing through the opening 8. In fact pure air is introduced into the interior without 105 any appreciable current being noticed.

To eliminate the foul air I provide end orifices 9, which are located at the end of the wall D⁹, the orifice 10 in the bottom 11, a deflecting plate 12, obliquely arranged deflecting plates 13 leaving an opening 14 and an upwardly extending vertical passage-way 15 and a downwardly extending passage-way 16 communicating with the chamber 17 110 formed beyond the deflecting plate 13. The foul air passes through the vertical passage-ways 15 and 16, the lower strata of air be-

ing taken by the passage-way 16. The air passes up in front of the back walls 17 and through the opening 14 and both ends of the deflecting plate 13 down through the opening 10 and out through the end openings 9 in the ends of the wall D⁹ and between it and the frame A. On account of the peculiar disposition of the projecting plates 12 and 13 and openings 10 and 9 no in-rush 10 of air will take place but the current of foul air will, I find in practice, pass outwardly and thereby remove all impure air from the room. The pure air is introduced in the upper portion of the casing as hereinbefore 15 described and it will thus be seen that there will be a continual circulation of the pure air into the room through the upper portion of the casing and foul air out from the room through the lower portion of the casing and 20 this too without any draft, which is one of the objects, which I specially desire to attain.

In Fig. 6, I show a modified form of my construction in which F is the lower sash 25 of the window with an opening F' formed in the lower rail thereof provided with a gauze screen F². F³ are the sides of the ventilator which are formed integral with the window sash. F⁴ is a board or plate extending outwardly from the window sash above the opening F' and in proximity with the back board F⁵ of the ventilator. F⁶ is 30 a top board extending from the back board in proximity with the window. By means of the boards F⁵ and F⁶ a circuitous passage is formed from the opening F' to the opening F⁷ leading into the room. By this construction the ventilator is formed integral with the window and is of course raised and 35 lowered therewith.

In Fig. 7, I show a further modification in which the ventilator is formed integral with the window as described in relation to Fig. 6 and is formed with side boards F⁸, bottom 45 board F⁹, back board F¹⁰, top board F¹¹ and with an intermediate board F¹² extending from the window sash above the opening F¹³ formed therein. Bars F¹⁴ and F¹⁵ depend from the board F¹² and a bar F¹⁶ extends 50 upwardly from the bottom board F⁹ of the ventilator into a position intermediate of the bars F¹⁴ and F¹⁵ thereby forming a circuitous passage F¹⁸ leading from the outside atmosphere to the opening F¹⁷ leading into 55 the room.

What I claim as my invention is:

1. A ventilating device for interiors comprising end walls, a top wall, a front wall,

a bottom wall and a back wall, the front wall extending below the bottom wall and having end openings and the bottom wall having an opening centrally disposed immediately behind the front wall, a deflecting plate located adjacent to the opening and extending toward each end wall and leaving 65 openings, obliquely disposed vertical walls extending from the back corners and leaving an opening in the center, and passage-ways extending inwardly from the space behind the obliquely set plates as and for the purpose specified.

2. A ventilating device for interiors comprising two portions, a fresh air inlet portion comprising front, back and top and bottom walls, the front wall having an opening 75 at the bottom thereof and the top wall having an opening at the top thereof diametrically opposite the opening in the front wall, and deflecting plates extending partially from the front wall inwardly and partially 80 from the back wall outwardly and interposed between the aforesaid deflecting plates and forming a circuitous passage-way from the bottom opening to the top opening, and a foul air outlet located beneath and connected to the fresh air outlet portions and comprising end walls, a top wall, a front wall, a bottom wall and a back wall, the front wall extending below the bottom wall and having end openings and the bottom 85 wall having end openings and the bottom wall having an opening centrally disposed immediately behind the front wall, a deflecting plate located adjacent to the opening and extending toward each end wall and leaving 90 openings, obliquely disposed vertical walls extending from the back corners and leaving an opening in the center, and passage-ways extending inwardly from the space behind the obliquely set plates as and for the purpose specified.

3. In a ventilating device for interiors, a casing having end walls, a top wall, a front wall and a bottom wall, the front wall extending below the bottom wall, a deflecting 105 plate located behind the front wall and having openings at the ends thereof between it and the side walls, and an obliquely disposed wall extending from the back corners forwardly and leaving an opening in the 110 center as and for the purpose specified.

JAMES ALEXANDER GLASS.
